Primary Examiner — Selina Sikder*(74) Attorney, Agent, or Firm* — Dykema Gossett PLLC(57) **CLAIM**

The ornamental design for a control box, as shown and described.

DESCRIPTION

FIG. 1 is a front perspective view of the control box seen from the top;

FIG. 2 is a rear perspective view seen from the bottom thereof;

FIG. 3 is a front elevation view thereof;

FIG. 4 is rear elevation view thereof;

FIG. 5 is a left side elevation view thereof;

FIG. 6 right side elevation view thereof;

FIG. 7 is a top plan view thereof; and,

FIG. 8 is a bottom plan view thereof.

The broken lines in the drawing depict portions of the control box that form no part of the claimed design.
